UNITED STATES PATENT OFFICE.

EMIL BOMMER, OF NEW YORK, N. Y.

SPRING-HINGE.

No. 825,104.

Specification of Letters Patent.

Patented July 3, 1906.

Application filed July 1, 1905. Serial No. 267,872.

To all whom it may concern:

Be it known that I, EMIL BOMMER, a citizen of the United States, residing in New York, in the borough of Brooklyn and State 5 of New York, have invented certain new and useful Improvements in Spring-Hinges, of which the following is a specification.

This invention relates to spring-hinges, and more especially to spring-hinges of that class 10 which are attached to the lower corners of the doors and operated in connection with a stationary socket-plate attached to the floor vertically below the hinge and a socket at the upper corner of the door with a connecting- 15 pivot in the door-casing.

The invention aims to provide a hinge of this type embodying improved means for tensioning and limiting the movement of the spring.

20 To this end the invention consists in the novel features and combinations of parts to be hereinafter described and claimed.

In the accompanying drawings, Figure 1 represents a side elevation of a door and door-casing with my improved spring-hinge applied to the lower and upper corners of the door and to the adjacent portions of the floor and door-casing, parts being broken off and other parts in section, so as to show the 25 30 35 40 45 spring-hinge in the lower corner of the door and the pivotal connection with the socket in the door-frame at the upper corner of the door. Fig. 2 is a vertical central section through the spring-hinge at the lower corner of the door, drawn on a larger scale. Fig. 3 is a top view of the hinge shown in Fig. 2, shown as detached from the door. Figs. 4, 5, and 6 are horizontal sections, respectively, on lines 4 4, 5 5, and 6 6, Fig. 2; and Figs. 7, 8, and 9 are details of the parts of the ratchet-plate by which the tension-collar is locked in position after the coil-spring is set to the proper tension.

Similar letters of reference indicate corresponding parts in the different figures of the drawings.

Referring to the drawings, D represents a door, and D' the casing of the same. The lower rear corner of the door is provided with 50 a recess of sufficient size to insert into the same a spring-hinge corresponding to the size and weight of the door. Below the spring-hinge and axially in line therewith is arranged a socket-plate B, which is provided 55 with wings b, that are attached by fastening-screws b^x permanently to the floor, said

socket-plate being provided with a tapering socket-hole b' of square cross-section for receiving the lower correspondingly tapered and squared end b² of a cast-metal frame F, 60 which is open at both sides and connected at its upper and lower ends, the connecting portions f f being provided with central openings for a pintle P, by which the connection of the fixed frame F with the inclosing frame or casing G of the spring-hinge is made. The ends of the pintle P are preferably upset after the parts are assembled, so as to hold them firmly together. The side walls of the stationary frame F are made arcuate in horizontal section, as shown clearly in Figs. 4, 5, and 6, the casing G being made with a curved outer wall adjacent to the side wall of the frame F and with a straight opposite wall, as shown also in Figs. 4, 5, and 6. The side walls of the 70 casing G of the frame F are connected at the upper and lower ends, the ends being provided with an opening for seating the cylindrical end portion of the frame F in the lower part of the casing G and with an opening in 80 the upper part for permitting the passage of the pintle P through the same. The casing G is further provided with a segmental extension g at the upper end in line with its outer curved side wall and with an extension 85 g' at the lower end, which is located at right angles to the side walls of the casing, said extensions g g' being provided with tapering holes for the fastening-screws g², by which the casing is attached to the lower rear corner 90 of the door, as shown clearly in Fig. 2.

In the interior of the tension-frame F is arranged a coil-spring S of sufficient power so as to move the door from the open to the closed position. The lower end of the coil-spring S is bent inwardly, as customary in spring-hinges, the inwardly-bent end being inserted in a recess of the lower spring-holder H. The upper end of the coil-spring S is also provided with an inwardly-bent end which 100 enters into a recess in the upper spring-holder H', said spring-holder being made in one piece with a tension-collar H², which is provided with radial holes for inserting a lever-pin by which the coil-spring is set to tension. 105 The upper end of the tension-collar H² is provided with ratchet-teeth r, which, as shown in Fig. 9, engage teeth r³ and r⁴ at the under side of a ratchet-plate R, which is provided with diametrically opposite lugs r' and r'', of 110 which one is shorter than the other, the shorter lug engaging the stationary frame F

and the longer lug engaging the curved side wall of the casing G, as shown clearly in Fig. 4. The lower spring-holder H is provided with diametrically opposite lugs h' h^2 , which in like manner respectively engage the opposite edges of the frame F and of the curved side wall of the casing G, as shown in Fig. 6. The spring-hinge after being placed in position is inclosed by a sheet-metal shell I, which is attached to the curved side wall of the casing G by fastening-screws i and to the opposite sides of the door by means of fastening-screws i' . The inclosing shell I, of sheet metal, protects the hinge against the entrance of dust and other obstructive matters. The inclosing shell I is provided at the upper and lower ends with small holes o for permitting the insertion of the spout of an oiler for injecting some lubricating-oil to the upper end of the casing G, which is slightly dished, as shown in Fig. 2, and to a washer w , interposed between the lower end of the frame and the lower spring-holder H. An antifriction ball-bearing M is inserted at the upper end of the casing, as shown in Fig. 2, and the oil is conducted along the pintle P to the bearings of the hinge, so as to properly lubricate the same and permit thereby the easy and noiseless moving of the spring-hinge in opening or closing the door.

The upper end of the door is held in position by the pivot-pin P', which is slidably connected to a cast-metal socket P², provided with a plate P³, that is cast integrally therewith, said plate being attached to the door-casing opposite the upper rear corner of the door. The pivot-pin P' is axially in line with the pintle of the spring-hinge at the lower rear corner of the door. The socket P² is provided with a slot p , through which passes a spring-rod P⁴, that is rigidly attached at one end to a lug on the plate P³, while at the other end it loosely engages a hole in the pivot-pin P'. An aperture o' in the plate P³, vertically below the pivoted spring-rod P⁴, permits the insertion of the end of a screw-driver, nail-set, or pin, so that the pivot-pin P' can be sufficiently raised when the door is to be taken down and its lower end withdrawn from the socket P⁵, that is inserted in the top of the door. When the door is to be replaced in position, the pivot-pin P' is pushed back flush with the face of the socket-plate P³, the recoil of the spring P⁴ causing the pivot-pin P' to enter the socket P⁵ as soon as it comes in line therewith. The socket P⁵ has a plate cast integrally therewith and is attached by screws to the top of the door axially in line with the pintle of the spring-hinge, as shown in Fig. 1.

The operation of the improved spring-hinge is as follows: Supposing the door to be in the position shown in Fig. 1, when the same is pushed outwardly—viz., toward the observer—the arcuate rear portion or wall of

the casing G will describe an arc in the opposite direction, carrying with it the lug r^2 , against which it abuts, as shown in Fig. 4, and consequently the upper spring-holder H', which in partially rotating upon the pintle, sets the spring S to tension, the frame F remaining stationary. The lower spring-holder H also remains stationary as the arcuate portion of the casing G is moved away from the longer lug h^2 . It is obvious that as soon as said arcuate portion forces the lug r' into contact with the inner wall of the stationary frame and the lug r' into contact with the outer wall thereof the tensioning of the spring will cease and the movement of the door will be limited. As soon as the door is released it returns, through the action of the spring, to its closed position. When the door is opened in a direction opposite to that just described—viz., when pushed backwardly from the position shown in Fig. 1—the lower spring-holder H will be partially rotated in the stationary frame F by the arcuate rear wall of the casing G, which, as will be seen from Fig. 6, will impinge upon the lug h^2 , and thereby partially rotate said holder in a direction opposite to that in which the upper holder is moved during the movement first described and set the spring to tension. This movement continues until the long lug h^2 strikes the rear wall of the stationary frame and the short lug h' strikes the front wall of the same, when the tensioning of the spring ceases and the movement of the door is limited in the manner previously explained. It is manifest that when the door is released it will swing back to its initial position under the influence of the tensioned spring.

During the movements described the door is efficiently pivoted at its upper edge by the pivot-pin P', as will be understood.

It is obvious that the spring-hinge above described can be applied to the upper rear corner of the door and the socket-plate to the casing adjacent thereto, while the pivot-pin can be applied to the floor and the socket in which it swings inserted into the lower rear corner of the door without departing from the spirit of this invention.

Having thus described my invention, I claim as new and desire to secure by Letters Patent—

1. In a spring-hinge, the combination, with a casing mortised in the door and comprising spaced outer and inner walls, of a frame disposed within said casing and fixed with respect to the door, said frame likewise including spaced inner and outer walls, a pintle passing downwardly through said casing and stationary frame, a helical spring in said frame surrounding said pintle, and spring-holders attached to the respective ends of said spring and rotatable about said pintle and each having diametrically-disposed lugs associated therewith, certain lugs of said two

holders normally abutting against opposite edges of the outer casing-wall, while other of said lugs engage the inner wall of the stationary frame at opposite edges.

- 5 2. In a spring-hinge, the combination, with a casing open at both sides and mortised in one corner of the door, said casing embodying an upright outer or edge wall arcuate in horizontal section, of a frame disposed with-
10 in said casing and fixedly attached to the floor or other fixed support, said frame embodying an outer member disposed parallel to the arcuate wall of said casing and an inner straight wall, and being also open at the
15 sides, an upright pintle passing through said casing and stationary frame, a helical spring in said frame extending about said pintle,

and spring-holders respectively attached to opposite ends of the spring and rotatable about said pintle, and each having diamet- 20 rically-disposed lugs of different lengths associated therewith, the longer lugs of the two holders normally engaging the opposite edges of the arcuate outer wall of the casing, while the shorter lugs normally engage the 25 inner wall of the frame at opposite edges thereof.

In testimony that I claim the foregoing as my invention I have signed my name in presence of two subscribing witnesses.

EMIL BOMMER.
